UNITED STATES PATENT OFFICE.

IRENE WARREN, OF CHICAGO, ILLINOIS.

HOLDER FOR LANTERN-SLIDES, CARDS, &c.

1,111,422.

Specification of Letters Patent. Patented Sept. 22, 1914.

Application filed February 10, 1911, Serial No. 607,740. Renewed May 7, 1914. Serial No. 837,084.

To all whom it may concern:

Be it known that I, IRENE WARREN, a citizen of the United States, residing at Chicago, in the county of Cook and State of Illinois, have invented certain new and useful Improvements in Holders for Lantern-Slides, Cards, &c., of which the following is a description, reference being had to the accompanying drawings forming a part of this specification, in which corresponding numerals of reference in the different figures indicate like parts.

The primary object of my invention is to provide a frame or container for the reception, storage, protection and classification of lantern slides, photographers' negatives, cards, photographs, samples of cloth, scientific specimens, or any similar articles adapted to be preserved in a flat form and in indefinite numbers, said frame constituting a unit which shall be so constructed as to be used singly or arranged in cases of any predetermined dimensions.

A further object is to so construct said frame that each article may be readily placed therein or removed therefrom without disturbing the others and when so placed may be readily located and examined, and this regardless of the number of containers employed.

To these ends my invention consists primarily in a rigid frame element, preferably rectangular in form, in which is pivotally mounted a series of hinged or pivoted posts or shafts, having grooved or channeled arms, or supporting members which are yieldingly held normally in the plane of the frame but free to be moved out of said plane when it is desired to place articles therein or to remove them therefrom; all of which is hereinafter more particularly described and definitely pointed out in the claims.

In the drawings, Figure 1, is a front elevation of a case showing a number of units therein embodying the features of my invention, Fig. 2, is a side elevation thereof showing one of said units or frame members, withdrawn to permit the contents to be inspected, Fig. 3, is an enlarged side view in detail of one of said units showing the pivoted or swinging members, Fig. 4, is a transverse sectional view thereof, taken upon the line 4—4, Fig. 3, viewed in the direction of the arrow there shown, Fig. 5, is a sectional view in plan taken upon the line 5—5, Fig. 3, showing the manner in which the

pivoted supporting elements are adapted to swing laterally to permit the insertion or withdrawal of articles. Fig. 6 is a sectional view taken upon the line 6—6, Fig. 3, viewed in the direction of the arrow there shown, and Fig. 7, is a sectional view in detail taken upon the line 7—7, Fig. 2, viewed in the direction of the arrow there shown.

My improved container is adapted to be used either singly or in series, but inasmuch as a considerable number of them would ordinarily be used together it is desirable that a case should be provided to receive them and it is in this way that I have preferred to show them.

Referring to the drawings 1, Figs. 1 and 2, represents a rectangular box-like case adapted to receive a predetermined number of frames or containers which are uniform in size and construction. Each container consists of a rigid rectangular frame 2 preferably made of wood, which is fitted to slide loosely in the case 1, so that when in place the front edge of the frame will be substantially flush with that of the case. I prefer to provide extensions 3, upon the rear of each frame at top and bottom as shown in Figs 2, and 3, said extensions being integral with the top and bottom rails. Said rails and extensions are provided with grooves 4, Figs. 2, 3, 4 and 7, into which stop pins 5 secured in the top and bottom of the case, are arranged to project. Shoulders 6, are formed near the rear ends of said grooves to engage said pins when the frames are drawn outwardly and serve to limit their outward movement in the manner indicated in Fig. 2.

Mounted in each of the frames 2, are posts or shafts 7, which are pivotally secured at their respective ends to the inner edges of the horizontal rails preferably by means of pintles 7^a, Fig. 3, or in any approved way to permit said members to be partially rotated. Rigidly attached to and extending at right angles from each of the members 7, are arms 8, which are arranged in a common plane so that each supporting member with its several arms is equivalent to a gate, door or leaf adapted to be swung back or forth upon a vertical axis. Each of the arms 8, except those at the top and bottom is provided with grooves or channels 9 in its upper and lower edges respectively. The topmost arm however has a groove only in its lower edge and the lowermost arm in its up-

per edge. These grooves form counterparts to each other in adjacent arms so that when a "leaf" is swung laterally upon its pivot to bring the free ends of the arms out of the plane of the main frame, as shown in Fig. 5, any flat thin article of proper size may be pushed edgewise into the grooves and thereby supported. The device is especially appropriate for the preservation and classification 10 of lantern slides and photographic negatives and in Figs. 3, 4 and 5, I have illustrated the manner in which glass slides 10 may be inserted, withdrawn or stored. It will be noted that the supporting members or containers are so placed with reference to each other that the forward ends of the arms of one are just behind and near to the shaft of the other. I prefer to have the free ends of the arms project in one direction only, 20 and that toward the front so that when the frame is pushed back in the case any leaf which may chance to be in an abnormal position will be brought into contact with the adjacent frame and moved into the plane of the frame. In order to hold said containers normally in a common plane, an indentation 25 11, Fig. 6, is formed in the lower edge of the lowermost arm 8, which is adapted to be brought into frictional engagement with the rounded head of a pin 12, see also Figs. 3 and 5, which is permitted to have a slight vertical movement in a bore formed in the lower bar of the frame 2, and is pressed upwardly by means of a coiled spring 13. 30 When the arm is in the plane of the frame the container as a whole will be yieldingly held in its normal position, but when it is necessary to insert or withdraw a slide, a slight lateral pressure will cause the container to swing upon its axis in either direction.

When the slides are all inserted in the containers in proper order, the several frames are pushed back in the case as shown in Fig. 45 1, where they are protected from dust or injury. Each frame may be designated by any predetermined number, legend or label 14, upon its front by which the contents of the containers therein may be indicated, and 50 whenever it is desired to examine a given frame the handle 15 thereof is grasped and the frame is drawn outwardly to its full limit. The case should be so placed that when so withdrawn every lantern slide will 55 be between a source of light and the person examining it. This enables any particular slide to be recognized and withdrawn at once.

In order to classify the contents of the 60 containers, I prefer to form grooves 16 upon opposite sides of each arm for the reception of labels. The labels in the grooves upon one side may be permanent in order to identify the slides which should bear corresponding labels 65 or marks, while the labels in the grooves upon

the opposite side may be removable. Such a system would enable different persons to use the slides and by inserting the proper label upon the removal of a given slide, all those outstanding could be accounted for, thereby enabling the slides to be systematically classified and accounted for at all times, which is of vital importance where the collection is voluminous. 70

The device is especially applicable to the 75 use of museums, universities, schools and colleges, or any institution or business house in which classification of the character indicated may be desired. For preserving scientific specimens it may be found desirable 80 to make the frames and leaves from sheet metal.

I do not wish to be confined to the exact 85 construction shown inasmuch as it may be varied in detail within the scope of the appended claims.

Having thus described my invention, I claim:

1. In a device for holding lantern slides or other transparencies, the combination with 90 an open rectangular frame, of a plurality of shafts pivotally mounted between two sides of the frame, spaced arms extending from one side of the shafts and provided with means adapted to receive and hold lantern 95 slides or other transparencies between them, the length of the arms being less than the distance between adjacent shafts whereby the lantern slides or other transparencies will normally lie in the same plane and 100 within the frame, for the purpose set forth.

2. In a device for holding lantern slides or other transparencies, the combination with 105 an open rectangular frame, of a plurality of shafts mounted upon two sides of the frame, 110 arms extending from one side of the shafts, said arms being provided with grooves in their opposite sides to seat and hold lantern slides or other transparencies between them, the length of the arms being less than the distance between adjacent shafts whereby 115 the lantern slides or other transparencies will normally lie in the same plane and within the frame, for the purpose set forth.

3. In a device for holding lantern slides or 120 other transparencies, the combination with a casing, of a series of open rectangular frames slidably mounted in the casing, each 125 of said frames being provided with a plurality of shafts pivotally mounted between the two sides of the frame, spaced arms extending from one side of the shafts and provided with means adapted to receive and hold lantern slides or other transparencies between them, the length of the arms being less than the distance between adjacent shafts whereby the lantern slides or other transparencies will normally lie in the same plane and within the frame, for the purpose set forth. 130

4. The combination with a case having parallel grooves therein, of a plurality of parallel rectangular frames slidably arranged in said grooves adjacent to each other, each of said frames having vertical posts pivotally mounted therein at top and bottom and a series of forwardly extended longitudinally grooved arms upon each of said posts and arranged at right angles there-
10 to, with their free ends extending toward the front of the frame, all of said posts being in a common plane, whereby said arms if projecting laterally may be caused to im-

pinge upon an adjacent frame when a given frame is pushed into place, thus causing 15 them to be moved into a common plane without danger of accident or injury thereto.

In testimony whereof, I have signed this specification in the presence of two subscribing witnesses, this eighth day of February 20 1911.

IRENE WARREN.
